UNITED STATES PATENT OFFICE

JAMES A. CAMERON, OF BUFFALO, NEW YORK

MULTIPLE MANIPULATING SUSPENSION ARM

Application filed February 1, 1926. Serial No. 85,319.

My invention relates to improvements in multiple manipulating supports in which the standard American desk telephone is attached to a multiple extension support which may be attached in a greater variety of locations and permit desired use positioning; and the principal objects of my improvements are, first, to provide a convenient upright rest position for the telephone clear of the desk and means for easily bringing the telephone into use position over the desk and clear of the ordinary desk work on hand, and various positioning and adjusting means for adapting the device to general use demands; second, to provide means for automatically making or breaking the electrical circuits when the telephone is moved into use or rest position respectively, and adjustable means for holding the telephone receiver when in rest or use position.

I attain these objects by the mechanism illustrated in the accompanying drawings, in which—

Figure 1 is a side view of the entire device, comprising the multiple support and showing the telephone in upright or rest position; Fig. 2, a side view showing the telephone partially inverted and in use position; Fig. 3, a plan view of the mechanism as shown in the preceding figure; Fig. 4, an inverted plan view of the self balancing frame; Fig. 5, an end view of the friction cam, and being a part of the mechanism of the tilting frame; Fig. 6, a side view of the cam; Fig. 7, a side sectional view of the cam and elongated slots for guiding the friction-shoe which contacts on the surface of the cam; Fig. 8, is a side view of the electrical telephone circuits, the weighted make and break circuit controlling means and the bell-box; Fig. 9, a side view of a friction retarding clamp used on the extension members of the support; Fig. 10, is a side view of the telephone receiver and adjustable clamp on the receiver holding rod.

Similar numerals represent similar parts in the various drawings.

The base 1, resting on the desk, the rod 2 threaded on the lower end and with a hole 7 near the upper end thereof, the grip-nut 3 the set-screw 4 for setting the rod 2 in the

base 1, the set-collar 5 set on the rod 2 over the base 1 by the set-screw 6, constitutes the support upon which the entire device is swung. Inserting a pin or rod in the hole 7 and turning to draw the grip-nut 3 and base 1 together will clamp the device firmly on the desk when the set-screw 4 may be tightened on the rod 2, and the collar may then be adjusted on the rod 2 to the desired raised position.

The lazy-tong 8 has a swivel 9 adapted to be frictionally retarded or bound on the rod 2 by the set-screw 10, a post 11 which may be adjusted in various raised locations on the swivel member 9, a forward swivel 12 with a pin 13 set therein and a friction retarding clamp 14, more clearly shown in Figure 9 and adapted to adjustably bind moving members of the lazy-tong, constitutes one extension unit of the support.

The other extension unit of the support lazy-tong 15 is composed of a rear swivel 16 pivoted on the pin 13 and may be frictionally retarded or bound thereon by the set-screw 17, a post 18 adapted to various raised adjustments on the swivel member 16, a forward swivel 19 with a pin 20 set therein, a friction retarding clamp 21, more clearly shown in Figure 9, a roller 22 on the upper end of the post 18, a control rod 23 having one end pivoted to one of the moving parts of said lazy-tong and the extended portion resting on the roller 22 and beyond said roller provided with a clamp 24. The forward end of clamp 24 slopes down to a projection 25 and back into a rest-slot 26 and ends in a stop 27 with a set-screw 28 for setting the clamp 24 firmly on the rod 23. The clamp 24 serves as a limit gauge on the extension movement of lazy-tong 15 and holding same in use position, and the projection 25 acts as a slight resistance to folding said lazy-tong thus holding the telephone more firmly in use position.

The rear end of the U shaped supporting arm 29 swivels on the pin 20 and is adapted to be frictionally retarded in movement or bound on said pin by the set-screw 30.

A tilting-frame 31 is pivoted 32 in the outer end of the supporting arm 29 and is

formed like a U shaped plate with the sides bent downward and provided with clips 33 on the forward end and an adjustable clip 34 and set-screw 35 fastened on the rear end. Said clips are adapted to clamp the telephone base 36 firmly to the upper surface of said tilting-frame. A pair of spaced elongated slots 37 37 are located within the U shaped supporting arm 29 and having one end attached to the rear thereof and the other 5 ends to the pivotal pin 32. The forward end of the tilting-frame 31 has a lug 38 bent downward and an adjusting screw 39 pivotally set therein. The cam member 40 is bent U shaped and the semi-circular shaped sides 10 extending downward from the base thereof have flanges 41 bent inwardly at right angles and have gradating dents 42 sloping inwardly near the rear limit of surface, and said sides have longitudinal slots 43 punched 15 close to the base thereof and through which is inserted the pivotal pin 32. The rear of the cam 40 has a threaded lug 44 bent downward and the adjusting-screw 39 threaded therein 20 for the purpose of adjusting said cam. The outer ends of the friction shoe 45 are inserted through the slots in guides 37 37 and have friction surfaces 46 machined thereon 25 conforming to the circular inner surfaces of the flanges 41. A tension-spring 47 is connected to the pin 45 and attached to the rear of the U shaped supporting arm 29. Turning the set-screw 39 to move the rear of the cam 40 closer to the pivotal-pin 32 will give 30 greater tension pull to the spring 47 as the telephone nears the horizontal and partially inverted or use position. These adjustments will be made to arrive at the desired set given to the telephone use position. The tension 35 spring 47 should be regulated to cause the telephone to return automatically to rest position when the outer end of the telephone is given a slight toss upward off use position, and as the telephone nears its upright or rest position the friction-shoe 45 will engage the 40 dents 42 42 on the rear of the cam 40 and slow up the return motion and the shock-absorber 63 will cushion the final rest movement. 45

The rear end of the tilting-frame 31 extends beyond the telephone base 36 and is provided with a pair of adjusting standards 50 50 punched and formed upward in said frame. The legs of a U shaped clamping 50 arm 51 are pivotally pinned 52 in the extended portion of the frame 31 and slide between the arms 50 50 and are provided with a bolt and set-nut 53 adapted to clamp the standards 50 50 within the head of said bolt 60 and the nut 53 against the legs of said arm 51, and a tubular spacer 54 through which said bolt is inserted aids in firmly holding said legs against said standards. A right lower and left upper bend plate 55 is formed 65 over the top of arm 51 and a pivotal-pin 56

passes through the lower end of the resilient receiver holding rod 57 and the arm 51 and plate 55. The lock-bar 58 is pivoted 59 on the top of the upper bend of said plate 55 and is provided with snap dogs 60 61 normally held projecting over the rod 57 by the tension-spring 62 connecting the rear end of the bar 58 and the pin 52 and provides a position lock for the rod 57 resting on the right lower bend of plate 55. 70

The cylinder 63 is suitably located on the supporting arm 29 and provided with a piston 64 fitting therein and with a push-spring 65 placed between the bottom of said cylinder and piston and is adapted to cushion the movement of the tilting frame 31 when about to seat in its normal rest position and acting as a pneumatic shock-absorber. 75

The ball 66 is integral with or may be set on the outer end of rod 57 and is gripped between one end of two clamping members 67 67 the other end of which grips the end of the telephone receiver 68 and said members and receiver are held in desired position 80 on said ball by the set-screw 69. 85

The circuit control means or switch hook 70 is weighted 71 on one end and pivoted 72 on the other end within the telephone post 85 and provided with a bell-crank or projection 73 pivotally connected with a link 74 leading to and pivoted on one end of a contact spring 75 adapted to engage with the contact 76, electrically 78 connected to the transmitter 79 and receiver 68 as in standard telephone circuit practice, when the telephone is approximately supported horizontally or partially inverted and in use position, and to engage the contact 80, electrically 81 connected to the bell-box 82 as in standard practice, when the telephone is in upright or rest position when the weight 71 forces the circuit controlling means 70 downward and breaks the transmitter and receiver circuits, as represented by the position indicated in the dotted line of Figure 8. 90

The inner end of the tubular sleeve 90 is pivoted 91 to the desired moving part of the lazy-tong 15 and the other end has inserted therein the rod 92 pivoted 93 in the outer end of the tilting-frame 31. The rod 92 may be set in the sleeve 90 by the clamp and set-screw 94 in desired relation. The moving part of the lazy-tong 15 which may be located farther or nearer the post 18 to which the rear end of the sleeve 90 is pivoted 105 will control the less or greater movement respectively transmitted to the tilting frame 31 in comparison with the extension travel of said lazy-tong. 110

When desiring to use the telephone, grasp 125 the post 85 and draw toward you. As the lazy-tong 15 extends it will be noted that the member to which the sleeve 90 is pivoted increases its distance from the pivotal pin 130 32 causing the rod 92 pivoted on the pin 93

to draw the tilting-frame 31 downward until the telephone is in the desired use position, which position when once determined the user may proceed to tighten the set-screw 10, and clamp 14, and the set-screw 28 of clamp 24 adjusted so the roller 22 rests in the slot 26. The receiver holding rod 57 may be adjusted to permit the receiver to be located in suitable position for the ear and the set-screw 53 tightened and also the set-screw 69. If it is desired to use the receiver at the right ear, lift the lower end of rod 57 past the dog 60 and swing the receiver over to the right side past the dog 61 which serves to hold the receiver in required position when the telephone is returned to rest position or brought into use position. When through telephoning give the transmitter end of the telephone a slight toss upward and the lazy tong 15 will fold backward and the telephone arrive at rest position and the weight 71 will fall and automatically break the talking circuits and make the bell-circuit.

If desired, the sleeve 90 and rod 92 may be removed, and manually tilting the telephone into use or rest position resorted to. The set-screw 21 may be tightened should sufficient clearance be found for ordinary desk work when the telephone is merely returned to upright rest position and without extending and folding the lazy-tong every time the telephone is used. The supporting-arm 29 may be swiveled into suitable angle and the set-screw 30 tightened, the multiple swivels permitting various adjustments of telephone positioning.

What I claim is—

1. In combination, a base, a support hinged to said base and comprising a plurality of separately operating extensible units, flexibly connected to each other and only movable along definite directive planes, and adapted to be manually controlled separately or together to extend in varying and distinct angles of travel to each other.

2. In combination, a telephone, a telephone support movable to locate the telephone in use or rest position, and adjustable means carried by the support and limited in function to regulating the resistance in the movement of the support, for the purpose described.

3. In combination, a telephone, a collapsible and extensible support for the telephone, means connected to the support and controlled by the movement of said support to automatically limit the extension movement thereof, and adjustable means operating in conjunction with the support and said first mentioned means for varying and setting the limit of said extension movement.

4. In combination, a telephone, a collapsible extension member for supporting the telephone and separate means attached to the member and limited in operation to auto-

matically increasing the starting resistance in the folding movement of said member, for the purpose described.

5. In a telephone support, a standard telephone, a tilting frame pivotally connected to the support and attached to the telephone and adapted to be radially moved on the support to locate the telephone in definite rest or use positions, and means carried by said frame for setting the telephone in either of said positions.

6. In a telephone support, a telephone instrument comprising a standard, a tilting frame pivotally connected to the support and attached to the telephone and adapted to be radially moved to position the telephone in upright unobstructed rest position, and adjustable means connected to the frame and support for holding the telephone in inverted use position.

7. In combination, a telephone, a movable support for the telephone, a tilting frame attached to the telephone and pivotally connected to the support, and connection between the frame and the support adapted automatically to radially tilt the telephone upon the movement of the support or to control the support by the radial tilting of said frame.

8. In combination, a telephone, a support adapted to be moved to and from the telephone user, a tilting-frame attached to the telephone and pivotally connected to the support, said frame being normally positioned horizontally and adapted to hold the telephone in upright rest position, and connection between the frame and the support adapted to automatically move said support forward or reverse upon tilting the telephone radially from rest to use position, or reverse, respectively.

9. In combination, a support, a standard desk telephone, a tilting frame clamped to the telephone and pivoted to the support, an eccentric cam attached to the frame and a friction drag contacting with the surface of the cam, a spring connecting the support and the drag and adapted to counterbalance the weight of the telephone upon its radial movement downward on said support.

JAMES A. CAMERON.
